OIL CAN

Frank M. Schaefer, Chicago, Ill.

Application February 13, 1935, Serial No. 6,342

1 Claim. (Cl. 221—43)

This invention relates to new and useful improvements in oil cans and more particularly to an oil can having a movable spout.

One of the objects of the invention is to provide an oil can having a spout which may be moved to an inoperative position whereby to close the outlet of the can.

Another object of the invention is to provide a spout which may be pivoted backwardly upon the upper face of the can whereby to form a compact unit.

Another object of the invention is to provide an oil can having a groove in the upper face thereof, adapted to receive a pivotal spout when the same is in inoperative position.

Another object of the invention is to provide an oil can spout having a valve adapted to be moved into operative and inoperative position.

Another object of the invention is to provide a spout for oil cans which is adapted to be moved to various angular positions when in use.

With these and other objects in view the invention will be better understood by reference to the accompanying specification and the drawing wherein Figure 1 is a top plan view of the device in operative position with parts thereof in cross section.

Figure 2 is an elevational view.

Figure 3 is a cross section taken on the line 3—3 of Figure 2.

Referring more particularly to the drawing, 1 indicates a circular casing substantially flat and having a concavo-convex upper face 2 and a false bottom face 3. A flexible disk 4 is mounted in the bottom 3, the inner periphery of the bottom face 3 being beaded as at 5 whereby to support the disk 4. An annular bead of solder 6 is arranged at the junction of the inner edge of the bead 5 with the disk 4 to seal the disk in place.

The casing 1 has a neck portion 7 formed thereon and extending outwardly from the flattened portion 8, this neck being threaded as at 9. A cap 10 is provided with a reduced threaded end 11 whereby to provide a shoulder 12. The cap 10 is adapted to be screwed into the neck 7, and has mounted on the end 11 thereof a gasket 13 which is adapted to abut the outer end of the neck and shoulder 12 whereby to prevent leakage from casing 1.

The cap 10 is provided with a longitudinal passage 14 adapted to have communication with the casing 1 at one end and with a transverse passage 15 formed in one side of a stem 16 rotatably mounted in a transverse opening 17 formed in the head 22. The passage 15 is adapted to communicate with one end of a longitudinal passage 18 formed intermediate the ends of the stem 16. A transverse passage 19 in the opposite side of the stem 16 is adapted to communicate with the other

end of the passage 18. One end of the stem 16 is adapted to be riveted to a head portion 20 of a spout 21 with the face thereof in abutment with one face of the head 22. The passage 19 is adapted to communicate with the passage 23 in the 5 spout 21.

The stem 16 extends beyond the other face of the head 22 and has mounted thereon a washer 24. A screw 25 is adapted to be threaded into the tapped other end of the stem 16, whereby to 10 clamp the spout 21 to head 22.

The casing 1 is adapted to be filled with a lubricating liquid which is forced therefrom by intermittent pressure exerted upon the flexible disk 4 through the passages 14, 15, 18, 19 and 15 23 respectively.

When it is desired to cut off communication between the passages 14 and 15, the spout 21 may be moved backwardly into a groove 26 formed at one side of the face 2, as shown in 20 dotted lines in Figure 2, at which time the closed portion 27 of the stem 16 is in abutment with the outer end of the passage 14. In closed position, the device provides a compact unit which may be conveniently carried in a suitable pouch. 25

In use the spout is adapted to be arranged in the position shown in Figure 2, but can be moved in various angular positions with respect to the horizontal plane of the casing when so desired without closing communication between the passage 14 and the passage 15.

While I have shown one particular embodiment of my invention, it is to be understood that various modifications can be made in construction without departing from the spirit of the invention.

Having thus described my invention, what I desire to protect by Letters Patent is:

A device of the class described including a substantially flat container having an outlet at one 40 side thereof and a lateral groove in its upper face, said groove being tapered in plan and extending angularly with respect to the horizontal plane of said container, a closure for said container having a longitudinal passage adapted to communicate with said container, a head formed on said closure having a transverse passage therein, a stem rotatably mounted in said transverse passage having an S shaped passage adapted to communicate with said longitudinal passage 50 when in operative position, a curved spout, and a head formed on said spout having a transverse opening, one end of said stem being fixedly arranged in said last named transverse opening whereby to form communication to said spout 55 from said S shaped passage, said spout being adapted to be mounted in said groove when in inoperative position.

FRANK M. SCHAEFER.
